US0D1105873S

(12) **United States Design Patent** (10) **Patent No.:** **US D1,105,873 S**
(45) **Date of Patent:** **** Dec. 16, 2025**

(54) **BLADE**

(71) Applicants: **Richard M. Dawson**, St. Louis, MO (US); **Julie E. Dawson**, St. Louis, MO (US)

(72) Inventors: **Richard M. Dawson**, St. Louis, MO (US); **Julie E. Dawson**, St. Louis, MO (US)

(**) Term: **15 Years**

(21) Appl. No.: **29/845,629**

(22) Filed: **Jul. 8, 2022**

(51) LOC (15) Cl. **08-05**

(52) U.S. Cl.

USPC **D8/19**

(58) **Field of Classification Search**

USPC D7/649, 412; D8/5, 7, 14, 16, 19, 20, D8/47, 70, 92, 98; D15/17, 139; D21/731; D24/146

CPC A47L 13/08; B26B 3/00

See application file for complete search history.
